(57) **CLAIM**

The ornamental design for a lighting track adapter, as shown and described.

DESCRIPTION

FIG. 1 is a top isometric view of a lighting track adapter; FIG. 2 is a top view thereof; FIG. 3 is a bottom view thereof; FIG. 4 is a left side view thereof; FIG. 5 is a right side view thereof; FIG. 6 is a back view thereof; FIG. 7 is a front view thereof; and, FIG. 8 is a right side isometric view thereof showing relative placement of a luminaire.

The broken lines are included for the purpose of illustrating the portions of the lighting track adapter that form no part of the claimed design.

1 Claim, 8 Drawing Sheets
